JOHN BISHOP AND EDWARD P. HUGHES, OF DETROIT, MICHIGAN.

WEIGHING-MACHINE.

1,131,108.

Specification of Letters Patent.

Patented Mar. 9, 1915.

Application filed February 9, 1914. Serial No. 817,532.

To all whom it may concern:

Be it known that we, JOHN BISHOP and EDWARD P. HUGHES, citizens of Great Britain and the United States, respectively, residing at Detroit, county of Wayne, and State of Michigan, have invented certain new and useful Improvements in Weighing-Machines, of which the following is a specification.

10 This invention relates to weighing machines, and more especially to that variety thereof which are known as "platform scales," and it has for one of its objects the provision of an improved mechanism which 15 comprises a member operated by the platform so as to have a predetermined weight exert an increased counterbalance effect or resistance proportionate to the downward movement of said platform, said increased 20 leverage being imparted to said member in an entirely automatic manner, that is to say: without any aid of the operator in either shifting the weight or adding thereto.

The invention has, furthermore, for its 25 object the provision of means whereby the counter-balance weight will be retarded in its movement to the desired degree during the descent of the platform, so that the latter will descend evenly until the counter- 30 poise has been attained and without any vibration at that time.

Further objects of the invention will hereinafter appear and be more particularly defined in the claims.

35 The invention has been clearly illustrated in the accompanying drawings, in which similar characters denote similar parts and in which:—

Figure 1 is a face view of a weighing machine embodying our invention, the standard thereof being broken away to disclose the interior mechanism. Fig. 2 is a central section substantially on line 2 of Fig. 1.

Referring to the drawings, 10 denotes the 40 base of the weighing machine having a movable platform 11 which is adapted to receive the article to be weighed, this platform being supported in any desired or well-known manner on the main beam 12 which is ful- 45 crumed at 13 and is connected at its rear end, as at 14, to an upwardly extending rod 15. This rod has at its upper end a flexible band 16 which is wound around a drum 17 of substantially uniform diameter, so that 50 the latter will be rotated by the descent of the platform 11.

The counterweight, whereby resistance is offered to the rotation of this drum, is in the present instance carried by a member so formed as to increase this resistance by virtue of the weight becoming effective at gradually increasing distances from the center of said drum. This member comprises a lever shaped in the form of a parabola and designated as a snail S the outer surface of which is formed so as to have the successive points thereof gradually increasing in distance from the center of the drum 17, and the cord 18 is attached to said snail near the center thereof, as at 19. Attached to the lower end of the cord 18 is a weight W and the cord 18 is, by the descent of the platform 11, wound upon the snail, and in this manner the distance of the pulling point of the cord on the snail will therefore be gradually increased as the band 16 is pulled downwardly. This means that this increasing distance will naturally effect a proportionate increase in resistance, without adding any further load to the weight W.

In order to bring the parts primarily to balance, a shiftable counterweight such as w may be employed upon a lever or rod 20 attached to the drum 17 as clearly shown. In the present instance the mechanism is so organized that the downward movement of the platform to its limit, will rotate the drum and snail for a little more than one-half rotation, and a pointer or hand 21 attached to the spindle of the drum may cooperate with a dial 22 to indicate the load on the platform 11.

As above stated, means are provided for retarding the movement of the weight W so as to obviate the vibration or back-and-forth movement of the indicator hand when the mechanism has arrived near its point of balance, and we accomplish this object by providing a tube 23 which is closed at the bottom and filled with oil, and in which the weight may freely slide so as to allow said weight to rise without establishing a vacant space in the lower end of said tube, or in other words: to allow the oil above the weight to pass below the same during the ascent of the weight W. A by-pass tube 24 having a regulating valve 25 may be employed for increasing or decreasing the freedom of flow of oil from the upper portion of the tube into the lower end thereof, or vice versa. In order to maintain free vertical movement of the weight W within

the tube, while the upper end of the cord 18 will be deflected in accordance to the position of the snail, we provide a guide pulley 26 in conjunction with said tube.

It will be understood from the above that the capacity or range of the weighing machine depends not only upon the actual weight W , but also upon the formation of the snail which in the present instance has been designed so as to have its various points increase in distance from the center thereof in uniform units for uniform angles of rotation, and it is to be understood that this ratio of increase may be varied as desired, without departing from the spirit of the invention. Likewise it should be understood that such increase in "linear pitch" may be changed, and that other portions of the mechanism may be altered to suit the required conditions, without leaving the gist of the invention out of consideration.

We claim:—

1. A weighing machine comprising a load-receiving platform, a rotatable drum coöperatively connected therewith, a snail carried by said drum, a weight, and a flexible band for connecting said weight and snail, whereby when said snail is rotated the active point of connection between said weight and snail will be proportionately moved away from the center during the descent of said platform under load, a vertical liquid

containing tube containing said weight to retard the movement thereof, and a guide for said band attached to said tube for guiding the weight thereon.

2. A weighing machine comprising a load-receiving platform, a weight counterbalancing the same, means for automatically varying the resistance offered by said weight proportionately to the descent of said platform under load, a liquid-containing tube closed at the bottom loosely surrounding and for guiding said weight, and for retarding the upward movement of said counter-balancing weight.

3. A weighing machine comprising a load-receiving platform, a weight counter-balancing the same, means for automatically varying the resistance of said weight proportionately to the descent of said platform under load, a liquid containing tube containing said weight and a by-pass connecting the upper end and lower end of said tube and having a regulating valve for retarding the upward movement of said counter-balancing weight.

In testimony whereof we affix our signatures in presence of two witnesses.

JOHN BISHOP.
EDWARD P. HUGHES.
